(57) **CLAIM**

The ornamental design for a handheld toy communicator with slidable cover, as shown and described.

DESCRIPTION

FIG. 1 is a front perspective view of a handheld toy communicator with the slidable cover in the open position illustrating my new design;

FIG. 2 is a front elevation view thereof;

FIG. 3 is a right side elevation view thereof;

FIG. 4 is a left side elevation view thereof;

FIG. 5 is a rear elevation view thereof;

FIG. 6 is a top plan view;

FIG. 7 is a bottom plan; and,

FIG. 8 is a front perspective view of my new design with the slidable cover in the closed position.

The broken lines represent portions of the design that form no part of the claim.
